UNITED STATES PATENT OFFICE.

LINDSAY H. TIMMONS, OF DES MOINES, IOWA, ASSIGNEE OF ONE-HALF TO ALWIN C. HAFFNER, OF DES MOINES, IOWA.

HUMIDIFIER.

Application filed June 16, 1926. Serial No. 116,383.

An object of this invention is to provide improved means whereby water vapor may be added to and circulated with warm air used in the heating of buildings.

5 A further object of the invention is to provide means in combination with a warm air heater whereby the amount of water vapor supplied to and carried by the warm air from the heater may be regulated and 10 controlled.

A further object of the invention is to provide means in combination with a warm air heater whereby the amount of water vapor supplied to and carried by the warm 15 air from the heater is automatically proportioned to the temperature of the heater.

A further object of the invention is to provide a humidifier for use with warm air heaters wherein thermostat-controlled means 20 are employed to regulate the flow of water to a vaporizing pan within said heater.

A further object of the invention is to provide a humidifier for use with warm air heaters adapted for service connection with 25 a pressure water supply.

A further object of the invention is to provide a humidifier for use with warm air heaters which is inexpensive, positive and automatic in action, adjustable and capable 30 of easy installation in heaters already in use.

35 My invention consists in the construction, arrangement and combination of elements hereinafter set forth, pointed out in my claims and illustrated by the accompanying drawing, in which—

Figure 1 is a side elevation of my complete device as installed in a warm air heater for practical use, a portion only of a conventional heater being shown, partly 40 in section. Figure 2 is a horizontal section on the indicated line 2—2 of Figure 1, the heater parts being omitted. Figure 3 is a top plan view of the water flow regulating devices and their actuating connections.

45 It is common knowledge that the heating of air to be circulated through a building results in a lowering of the humidity of the air so heated with consequent loss of heating efficiency and ill effect on the occupants of a building so warmed. Various means have been employed from time to time, in combination with warm air heaters, having as an object the supplying of water vapor to the air circulated through said heater, but such means have required fre-

quent attention and have not been fully automatic in operation, nor have such means made provision whereby the humidity limits might be easily regulated at will. These and other objections are met and overcome 60 by the principles embodied in my device.

In the construction of the device as shown, the numeral 10 designates a side wall and the numeral 11 the top of the air chamber of a conventional warm air heater having a domed fire box as indicated by the numeral 12. A tubular standard or hollow pipe 13, threaded externally at its upper end, is mounted vertically through the top plate 11, projects above said plate and has 70 its lower end within the air chamber of the heater adjacent to and to one side of the crown of the fire box 12. A flanged collar 14 is adapted to slip freely on the standard 13 with its flange resting on the 75 plate 11, said collar being provided with a set screw 15 adapted to adjustably position and hold said standard against vertical displacement relative to said collar. A bracket 16 has one end formed with a hole adapted 80 to receive the standard 13, said end of the bracket engaging beneath the top plate 11 and collar 14, all of which are firmly bolted together by means of bolts 17 passing through registering holes in the flange of 85 said collar, said top plate and the end of said bracket. The bracket 16 extends from its attachment to the top plate 11 downwardly and away from the standard 13 across the dome of the fire box 12 to a point 90 on the opposite side of the crown of said fire box from the end of said standard, at which point the bracket is bent back across said fire box toward said standard and terminates in an off-set end formed with a hole adapted 95 to receive and embrace the lower end of said standard, whereby the latter is positioned and braced against lateral displacement.

A frame 18, is substantially rectangular in plan, is formed with webs 19 and 20 transversely of its open central portion and with a laterally extending curved arm 21, said arm terminating in an enlarged end portion 22 formed with an internally threaded bore adapted to receive and engage with the threaded upper end portion of the standard 13, whereby said frame may be supported above the plate 11 and laterally removed from the upper end of said standard. A nut 23 is screwed on the standard 13 below 110

the boss 22 and is adapted to engage beneath said boss after the frame 18 has been positioned and lock the boss 22, arm 21 and frame 18 in position relative to the standard 13. A shaft 24, of somewhat greater length than the standard 13, is mounted for rotation within said standard and projects beyond the standard at either end. A lever arm 25 is formed with an apertured boss at one end and is provided with a hole at right angles to the axis of its boss adjacent its other end and is clamped to the projecting upper end of the shaft 24 by means of a set screw 26, so that the lower surface of the boss of the lever arm bears against the upper surface of the boss 22 and the shaft is thereby positioned axially of the standard. A pipe 27 leads from any suitable source of water supply to an elbow 28 threadedly engaged in one end of the frame 18 with its open end toward the web 19. Holes are formed in the webs 19 and 20 in axial alinement with the open end of said elbow and a plunger 29, formed with a tapering end portion adapted to seat in and at times close the open end of the elbow 28, is mounted for horizontal reciprocation in said holes, longitudinally of the frame 18. An expensive coil spring 30 is mounted on the plunger 29 between the webs 19 and 20, one end of said spring bearing against the web 20 and the other end against a pin 31 carried by the plunger, to the end that said plunger is normally maintained with its tapered end engaging and closing the open end of the elbow 28. A pull rod 32 is formed with a short arm and an externally threaded longer arm at right angles to each other, the shorter arm being loosely received in a vertical hole adjacent the un-tapered end of the plunger 29 and the threaded portion of the longer arm passing through the hole in the outer end of the lever arm 25 and carrying a wing-nut 33 adapted to bear against the outer face of said lever arm and position said pull rod relative thereto. A stop screw 34 is threaded through the end of the frame 18 opposite to the elbow 28 and in alinement with the axis of the plunger 29, said stop screw being adapted to limit the movement of said plunger in one direction. A tube or pipe 35, preferably of copper or other rust resisting material, is formed with a funnel 36 on its upper end and a trap 37 adjacent said funnel and is mounted through the top plate 11 with said funnel slightly below the frame 18 and in such position relative to the discharge end of the elbow 28 as to catch the water discharged therefrom, the lower end of said pipe extending within the warm air chamber of the heater to a point above the crown of the fire box 12 where it is adapted to discharge into a relatively flat vaporiz-

ing pan 38, likewise of rust resisting material, carried by the lower horizontal portion of the bracket 16 in close proximity to said fire box. A bi-metallic thermostatic device of a common type, in this instance formed of concentric, interrupted circles of metals having different coefficients of expansion riveted or bolted together, is firmly bolted or otherwise secured to the vertical mid-portion of the bracket 16 in such manner as to surround the vaporizing pan 38 with the open ends of the interrupted circles adjacent and at either side of the lower end of the standard 13. The metal having the greater coefficient of expansion, 39, is within the band 40 of the metal having the lesser coefficient, and the ends of the band 40 extend beyond the ends of the ring 39 and terminate in eyes 41 adjacent the lower end of the standard 13. A toggle lever 42 is formed with a hub and oppositely extending radial arms, said hub being apertured to receive the lower end of the vertical shaft 24 to which the lever is clamped by means of a set screw 43 seated in said hub. The radial arms of the toggle lever 42 are formed with holes near their outer ends adapted to receive the ends of headed pins passed through the eyes 41, whereby the ends of the thermostatic device are connected to the arms of said toggle lever.

In the operation of my device, the component parts being assembled and connected as shown in Figure 1, the wing nut 33 is manually adjusted to withdraw the plunger 29, slightly, from its seat in the elbow 28, thus permitting a continuous supply of water to flow from the pipe 27, elbow 28, funnel 36, trap 37 and tube 35 to the vaporizing pan 38, where the heat from the fire box 10 vaporizes the water and the vapor thus formed is carried by the circulation of the heated air throughout the building and rooms served by the heater. The trap 37 provides against escape of the heated air 110 and water vapor from the hot air chamber. The rate of flow thus obtained may be visually gauged by means of the sight gap between the frame 18 and the funnel 36, and should be so adjusted as to furnish sufficient 115 water to maintain the desired humidity of the air at low heater temperature. When the temperature of the heater increases, the thermostatic device tends to expand and further separate at its ends. This tendency 120 of separation, by virtue of the connections hereinbefore recited, causes the toggle lever to be rotated in proportion to the expansion of the thermostat, thereby rotating the shaft 24 and consequently rotating the lever arm 25, which rotation withdraws the plunger 29 further from its seat in the elbow 28 and permits a greater flow of water 125 to the vaporizing pan 38, thus maintaining the desired humidity in spite of the increase 130

of heat and air circulation. As the temperature of the heater decreases, the spring 30 forces the plunger 29 toward its seat in the elbow 28 as rapidly as the contraction 5 of the thermostat will permit.

It is obvious that many structural and mechanical modifications of the specific construction shown are possible without departing from the spirit of my invention, hence I 10 wish to be understood as being limited only by the scope of the appended claims.

I claim as my invention—

1. A humidifier in combination with a hot air heater, comprising a hollow standard 15 mounted vertically through the top of said heater, a frame fixed to and carried by said standard, water supply means connected with said frame, a spring-pressed valve carried by said frame for controlling the flow 20 of water in said supply means, a vaporizing pan within said heater, water conducting means between said valve and pan, a heat-expansible device within said heater and rotatable means within said standard connecting 25 said heat-expansible device and valve whereby said valve may be actuated by the expansion and contraction of said device.

2. A humidifier in combination with a hot air heater, comprising a hollow standard, 30 a frame fixed to and carried by said standard, water supply means connected with said frame, a spring-pressed valve carried by said frame for controlling the flow of 35 water in said supply means, a vaporizing pan within said heater, water conducting means between said valve and pan, a vertical shaft mounted for rotation within said standard and projecting above and below 40 said standard, a lever arm on the upper end of said shaft, rotatable therewith, and connected to said valve, a toggle lever on the lower end of said shaft and a heat-expansible device within said heater and connected 45 with said toggle lever.

3. In a device of the character described, 50 a hollow standard, a frame fixed to and carried by the upper end of said standard, water supply means connected with said frame independently of said standard, a valve seat 55 on the end of said water supply means, a spring-pressed valve carried by said frame and adapted to register with said seat, a vaporizing pan beneath said valve, water conducting means between said valve and 60 pan, together with heat-expansible means and connections through said standard whereby said valve may be actuated by temperature changes.

60 4. In a device of the character described having a hollow standard, a frame carried by said standard, water supply means and a spring-pressed plunger control valve carried by said frame, the combination of a 65 vertical shaft mounted for rotation within

said standard, a lever arm fixed to the upper end of said shaft, adjustable connections between the end of said lever arm and said valve, a toggle lever fixed to the lower end of said shaft, a heat-expansible device supported extraneously of said shaft and connected with said toggle lever, whereby said shaft may be rotated by temperature changes effecting said heat-expansible device. 70

5. In a device of the character described having a hollow standard, a frame fixed to and carried by said standard, water supply means and a spring-pressed control valve carried by said frame, valve-operating means comprising a vertical shaft mounted for rotation within said standard, a lever arm fixed to and rotatable with said shaft, a pull rod adjustably connecting said valve plunger and lever arm, together with thermostat controlled means whereby said shaft may be rotated by and in proportion to temperature changes effecting said thermostat. 80

6. In a device of the character described, 85 an automatic valve comprising a substantially rectangular frame, webs transversely of the open central portion of said frame, a valve seat at one end of said frame, a valve plunger slidably mounted through 90 said webs and adapted to register with said seat, an expansive coil spring surrounding said plunger and confined between one of said webs and a pin carried by said plunger, an adjustable stop screw in the end of 95 said frame opposite from said valve seat and means connecting said plunger with a lever whereby said plunger may be withdrawn from said seat against the pressure of said spring. 100

7. In a humidifier in combination with a hot air heater, having a vaporizing pan within said heater and a water flow control valve without said heater, a vertical standard mounted through the top of said heater 110 and supporting said control valve, a bracket fixed to said heater and standard and supporting said vaporizing pan, together with water conducting means between said pan and valve, said means comprising a funnel 115 beneath and spaced from said valve, an S-shaped tube forming a trap beneath said funnel and a tube passing through a wall of said heater to connect said trap and vaporizing pan. 120

8. In a humidifier in combination with a hot air heater, a hollow standard extending within and without said heater, a frame on said standard without said heater, water supply and control means carried by said frame, a supporting bracket for said standard within said heater, a vaporizing pan supported by said bracket, connections for water flow between said supply means and pan, and thermostat-operated connections 125 130 135

through said standard whereby said control means may be actuated by temperature changes within said heater.

9. The combination of a hot air heater and a humidifier comprising a standard mounted vertically through the top of said heater, water supply and water flow control means carried by said standard without said heater, vaporizing means and a thermostatic control device positioned from said standard within said heater and connections, operable by said thermostatic device through said standard for adjusting and regulating the water flow control means automatically.

10. The combination of a hot air heater and a humidifier comprising a hollow standard mounted vertically through top of said

heater and having a fixed member including a water flow control valve on its upper end, a bracket extending laterally from said standard within said heater and supporting a thermostatic device, a vertical shaft toggle-connected at its lower end to said thermostatic device and extending through and above said standard, an arm fixed to the upper end of said shaft and connections between the end of said arm and said control valve whereby the flow of water through said valve is proportioned to the temperature of the heater.

Signed at Des Moines, in the county of Polk and State of Iowa, this 11th day of June, 1926.
